(57) **CLAIM**

The ornamental design for an egg poacher, as shown and described.

DESCRIPTION

FIG. 1 is a perspective view of an egg poacher showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective view in a use state thereof.

The broken lines depict portions of the egg poacher that form no part of the claimed design.

1 Claim, 7 Drawing Sheets
